UNITED STATES PATENT OFFICE.

NATHAN HARRIS, OF JAMAICA PLAIN, MASSACHUSETTS, ASSIGNOR OF ONE-THIRD TO
KARL M. GOLDSMITH, OF NEW YORK, N. Y., AND ONE-THIRD TO LOUIS HARRIS,
OF BOSTON, MASSACHUSETTS.

COAT-COLLAR.

977,866.

Specification of Letters Patent.

Patented Dec. 6, 1910.

Application filed November 16, 1909. Serial No. 528,612.

To all whom it may concern:

Be it known that I, NATHAN HARRIS, a citizen of the United States of America, and a resident of Jamaica Plain, in the county of Suffolk and State of Massachusetts, have invented certain new and useful Improvements in Coat-Collars, of which the following is a specification.

This invention relates to coats, overcoats, and similar articles of wearing apparel and has for its object the production of a garment of this class in which the collar is adapted to be turned over in the usual manner, showing a lapel, or to be buttoned up to the neck and thereby form a stand-up or military collar.

One of the principal objects of the invention is to provide a collar which is made double so that when one collar is exposed to view the other is entirely concealed, neither one of the collars affecting the appearance of the other.

Heretofore coats have been constructed with double collars but as far as is known the collars are so constructed that when folded over to form one of the collars a wrinkle is formed in the other collar hidden from view. This wrinkle or fold in the material is obviously a great disadvantage as it injures the appearance of the garment while it is apt to inconvenience the wearer. By constructing the collar in the manner shown in the present drawings and described in the present application these disadvantages are wholly obviated.

The invention consists in certain novel features of construction and arrangement of parts which will be readily understood by reference to the description of the drawings and to the claims hereinafter given.

Of the drawings: Figure 1 represents a front view of a coat embodying the features of the present invention and showing an ordinary turn-over collar. Fig. 2 represents a front view of the same coat when buttoned up to the neck and exposing to view the military or stand-up collar. Fig. 3 represents an outside view of the upper portion of the coat stretched out flat and showing the military collar. Fig. 4 represents a similar view of the inside of the coat and showing the ordinary turn-over collar. Fig. 5 represents an elevation of the collar portion before being attached to the garment and showing the military collar. Fig. 6

represents an elevation of the opposite side of the same showing the ordinary turn-over collar. Fig. 7 represents an enlarged sectional detail with a collar partially broken away to show the fastening tab for securing the two parts of the body portion together when the military collar is in use. Fig. 8 represents a similar detail showing the fastening tab secured in the position which it assumes when not in use beneath the military collar. Fig. 9 represents a transverse section of the collar portion of the garment and the fastening tab interposed between the military collar and the turn-over collar, the cutting plane being on line 9—9 on Fig. 70. Fig. 10 represents a section through the collar portion and a portion of the neck of the coat to which it is attached, the cutting plane being on line 10—10 on Fig. 2. Fig. 11 represents a similar section of the same parts when folded over to form a turn-down collar, the cutting plane being on line 11—11 on Fig. 1, and Fig. 12 represents an elevation of the fastening tab.

Similar characters designate like parts throughout the several figures of the drawings.

In the drawings, 10 represents the body portion of the coat to which are secured the usual facings 11 on the inner side thereof. 85 The neck of the coat is cut lower than in the usual practice as indicated at 12 (Fig. 4) and to this neck is secured the edge 13 of the turn-over collar 14. To the rear face of the collar 14 is secured a canvas strip 15 at either 90 end of the collar extending beyond the edge 13, as indicated in Fig. 6 of the drawings. To the opposite side of the canvas 15 is secured at its upper edge the military collar 16 and near its lower edge this collar is also 95 secured to the canvas strip 15 from 17 to 17.

When the coat is in use with a turn-over collar it is folded over substantially on the line 18—18 (Figs. 3 and 4) thus forming the lapels 19 and giving the collar the appearance as shown in Fig. 1. Should, however, the front of the coat be brought together and the button 20 passed through the buttonhole 21 the military collar 16 will be brought about the neck of the wearer giving the appearance as indicated in Fig. 2 of the drawings. The collar portion of the coat is maintained in this position by means of the fastening tab 22 having a buttonhole 23 at each end thereof, these buttonholes being adapted 110

to engage the buttons 24 secured to the outer face of the body portion of the coat beneath the military collar 16. When not in use for the purpose of securing the two ends of the 5 collar portion together around the neck of the wearer the tab is shifted around one of the buttons 24 as indicated in Figs. 3 and 8 of the drawings, and its opposite end is secured to the supplementary button 25 which 10 retains the tab in concealed position beneath the military collar.

The body portion 10 extends to the upper edge of the military collar 16 and is secured at its upper edge by blind stitches to the 15 outer edge of the turn-over collar, as indicated in Figs. 7 and 8 of the drawings. The edge 26 of the canvas strip 15 is secured by a plurality of blind stitches 27 to the outer body portion 10 of the coat.

20 As shown in Fig. 3 the lower edge of the military collar when in use is always above the fold 18—18 so that when this collar is folded over with the lapels 19 onto the body portion to form an ordinary collar there is 25 no fold through the military collar which is an advantage over the double-faced collars which are now in use inasmuch as the fold which is thus made in the military collar when the ordinary collar is in use soon be- 30 comes set and when the military collar is put in use the crease thus formed is exposed to view detracting from the appearance of the garment.

The usual stiffening members used in practice in the collar and other portions of the 35 coat are omitted in the various sectional views in order to simplify the drawings.

This construction of a double collar for coats and similar garments provides a means 40 whereby the coat may be used in two different styles either with a turn-over collar or a military collar neither of the collars of which are liable to be exposed to view being creased or otherwise injured when the other

collar is exposed to view. The advantage 45 of this is self-evident.

It is believed that the construction and many advantages of the invention will be fully understood from the foregoing.

Having thus described my invention, I 50 claim:

1. In a device of the class described, the combination of a coat, the outer portion of which extends considerably above the line of fold for the collar; an inner collar portion 55 extending above and below said line of fold and secured to the outer portion; and a military collar of less width than said inner collar portion secured thereto at their upper edges and secured near its lower edge to said 60 outer portion, with its lower edge when in use above said line of fold.

2. In a device of the class described, the combination of a coat having a turn-over collar; and a military collar secured to the 65 normally unexposed face thereof with its lowest edge when in use above the line of fold of said turn-over collar.

3. In a device of the class described, a multiple collar composed of two pieces of 70 material secured together at their upper edges the inner piece of which extends considerably below the lower edge of the outer piece and is secured to the inner facing of the garment while the outer piece extends 75 over the outer face of the neck of the body portion of the garment and is secured there- to at or near its lower edge whereby the in- 80 inner piece of said collar may be turned over on a line of fold immediately beneath the lower edge of said outer collar portion.

Signed by me at 4 Post Office Sq., Boston, Mass., this 2d day of November, 1909.

NATHAN HARRIS.
